HOSIERY DISPLAY DEVICE

Charles L. Craft, Randal R. Craft, and Sidney M. Craft,
Jackson, Miss.

Application February 7, 1955, Serial No. 486,482

2 Claims. (Cl. 206—45.33)

This invention relates to hosiery display devices, and in particular to wallet size packages adapted to clearly display all critical features of the hosiery contained therein.

A principal object of the invention is to provide an improved stand-up display package for hosiery, of novel shape and size adapted for convenience in packing, handling, display and automatic merchandising.

A particular object of the invention is to provide a package permitting the welt, seam and sheer leg portions of women's hosiery to be readily and simultaneously viewed through a transparent outer wrapper, effecting a display of outstanding sales appeal.

Another object is to provide in a hosiery display package a unique hosiery and sheet carrier unit, including means to maintain the unit arrangement and retain the stockings in place therein, proof against inadvertent displacement.

Other objects are to provide an attractive and inexpensive display device in which hosiery may be readily packed with minimum labor expense, and in which the hosiery may be effectively sealed and protected until purchased and used. Further objects of the invention will be in part obvious and in part pointed out hereinafter.

The invention and the novel features thereof may best be made clear from the following description and the accompanying drawings, in which:

Figure 1 is a top plan view of a preferred embodiment of the invention, containing a pair of women's hose;

Figure 2 is a sectional view, on enlarged scale, taken on the line 2—2 of Figure 1;

Figure 3 is a sectional view on enlarged scale, taken on a line 3—3 of Figure 1;

Figure 4 is a top plan view of a further embodiment of the invention, containing a pair of men's half hose or socks;

Figure 5 is a sectional view taken on the line 5—5 of Figure 4;

Figures 6 to 9 are a series of views showing sequentially the manner of folding and assembling the hosiery-sheet carrier unit of the device, and,

Figure 10 is an exploded view of a complete device corresponding to that of Figure 1, illustrating the assembly relationship of the parts thereof.

Referring to the drawings in detail, the preferred embodiment illustrated in Figures 1, 2, 3 and 10 includes a rectangular open top box or receptacle 20, which may be constructed of cardboard or the like. The receptacle 20 is relatively narrow and thin, and may be for example four inches wide and ten inches long, and three-eighths inch in depth. In the receptacle is positioned a hosiery-sheet carrier unit 21, comprising a pair of women's stockings 22, a sheet carrier 23, and suitable fastening means such as the illustrated piece of transparent, pressure-sensitive tape 24, which engages the welt ends of the stockings to the sheet carrier and maintains the unit relationship. An inside label 25 overlies the upper end of the unit 21, and the open top of the receptacle 20 is covered by a

2

transparent wrapper 26, which preferably encloses the entire device.

As best illustrated in Figures 6 to 9, the sheet carrier 23 corresponds substantially in length to the interior of receptacle 20, but is approximately twice as wide, corresponding in width approximately to the width of the welt ends of the stockings 22. The sheet 23 is longitudinally creased at 27 intermediate its sides 28, to facilitate folding along the crease line. To assemble the unit 21, a sheet 23 may be placed over the welt ends of a pair of stockings 22, the stockings being laid out flat as illustrated in Figure 6, with the upper edge 29 of the sheet in substantial coincidence with the upper edges 30 of the stockings.

Thereafter, the lower portions of the stockings may be folded up and over the lower edge 31 of the sheet, as illustrated in Figure 7, and then refolded so as to lie entirely within the confines of the sheet, as illustrated in Figure 8. The sheet 23 may then be folded along its crease 27 inwardly to enclose the lower portions of the stockings between its sections, and the upper end of the assembly may be fixed in position in some convenient manner, as by means of the tape 24. Preferably, the tape 24 extends over the upper edges 29 of the sheet sections and engages the upper edges 30 of the stockings on either side thereof to each other and to the upper edges of the sheet. The sheet carrier and stockings are thus simply joined into a relatively stable unit which may be readily handled.

The unit 21 so assembled may then be placed into the receptacle 20, which, as will be evident, is only one half the width of the stocking welts. If desired, an inside label 25 may be placed over the upper end of the unit before placement in the receptacle. As shown in Figures 3 and 10, the inside label 24 may be constructed of paper or light cardboard, folded to comprise a front panel 32, end panel 33 and a short back panel 34. As will be clear, when the label is positioned over the upper end of the unit in the manner illustrated, the end and back panels 32 and 33 thereof serve effectively to retain the label front panel 32 in place.

If the stockings 22 are seamless, it is relatively unimportant which side of the unit 21 is uppermost in the receptacle 20. In either case, the welt and sheer leg portions of the stockings will be clearly visible through the open top of the receptacle, permitting a customer to see at a glance the critical features thereof. Additionally, the color and shade of the hose are apparent, particularly if the sheet carrier 23 is white or light color, for contrast. If the stockings have seams, as a further feature of the invention, the unit 21 may be placed in the receptacle 20 with the seamed sides of the stockings uppermost, that is with the stocking seams overlying the upper section of the sheet 23. In such case, the welt portions, sheer leg portions and seams of the stockings are all presented upwardly to the open top of the receptacle, whereby all three features may be readily and simultaneously viewed. Moreover, these features are displayed in a relatively narrow package, a consequence of the longitudinal folding of the welt ends of the stockings.

With the unit 21 positioned in the receptacle 20 as described, and also an inside label 25 if such as desired, the open top of the receptacle may be covered by a transparent wrapper 26, or the receptacle may be entirely enclosed by the transparent wrapper. An outside label may be printed on or applied to that portion of the wrapper overlying the open top of the receptacle, and the overlying wrapper portion may also be provided, if desired, with a decorative border. The underside of the receptacle 20 may in similar manner be provided with advertising material.

When the device has been completely assembled, the

3

tape 24 serves to effectively retain the upper portions of the stockings adjacent the upper edge of the sheet carrier, so that the displayed stocking portions may not slip downwardly within the package. The resultant device has unusual sales appeal, in that it presents for ready inspection all critical features of the hose contained therein, and also provides effective protection for the hose and convenient form for packing and handling.

Another embodiment of the invention, suitable for the packaging and display of men's half hose or socks, is illustrated in Figures 4 and 5. In this modification, a sheet carrier 23' of single thickness may be utilized, that is the sheet carrier may conform roughly to the dimensions of the receptacle 20. The sheet carrier preferably is provided with an oblique lower edge 35, and the upper portions of the socks 36 are disposed above the sheet 23' in the manner illustrated, with the heel portions 37 thereof aligned with the lower corner of the sheet. The oblique lower edge 35 of the sheet accordingly permits the toe portions 38 of the socks to be folded under the sheet in general alignment with the upper portions thereof. As in the case of the embodiment previously described, suitable fastening means such as a small piece of tape 24' may be employed to detachably engage the upper edges of the socks to the sheet 23', adjacent the upper edge thereof. As will be evident, in this embodiment also the device is adapted to display through the transparent wrapper all critical features of the hose contained therein.

It will thus be seen that there has been provided by this invention a structure in which the various objects hereinbefore set forth, together with many practical advantages, are successfully achieved. As various possible embodiments may be made of the mechanical features of the above invention, all without departing from the scope thereof, it is to be understood that all matter hereinbefore

4

set forth or shown in the accompanying drawings is to be interpreted as illustrative, and not in a limiting sense.

We claim:

1. A hosiery display device comprising a rectangular open top receptacle, a rectangular sheet carrier in said receptacle, said sheet being approximately the width of the welt end of a stocking and twice the width of said receptacle, said sheet being longitudinally folded intermediate its sides into upper and lower sections, a pair of stockings disposed with the upper portions thereof wrapped externally about said sheet, the welt ends of said stockings adjoining the upper end of said sheet, and the lower portions of said stockings being wrapped about the lower end of said sheet and folded between the upper and lower sections thereof, means engaging the welt ends of said stockings to the upper end of said sheet, a label being folded over the upper end of said sheet carrier and stockings, and a transparent wrapper covering the open top of said receptacle, through which the label and the welt portions and adjoining portions of said stockings may be viewed.

2. The structure defined in claim 1 wherein said stockings are arranged on said sheet with the seams of said stockings disposed over said upper section of said sheet.
